CONTAINER

Albert John Meier, Glendale, Mo.

Application June 15, 1935, Serial No. 26,763

2 Claims. (Cl. 150—10)

My invention relates to novel apparatus for and methods of operating a closure and more particularly relates to novel containers for coins, keys, jewelry, paper, badges, cosmetics, and the like.

Heretofore, attempts have been made to develop a container having a simple automatic and effective closure. To this end, the usual snap fastener closures for bags and the like have been replaced by zippers and tension operating members. These, however, are still involved and expensive and in the case of the zippers, are not automatic.

Accordingly, an object of my invention is to provide a novel closure for containers.

A further object of my invention is to provide a container having a novel automatic closure.

A still further object of my invention is to provide automatic deflecting means in a container for preventing accidental spilling of the contents.

Still a further object of my invention is to provide a container having freely mounted therein an automatic closure device.

Still another object of my invention is to provide a simple and durable container which can be constructed at low cost.

There are other objects of my invention, which together with the foregoing, will appear in the detailed description which is to follow in connection with the drawings, in which:

Figure 1 is a top plan view of one embodiment of my invention.

Figure 2 is a side elevation of the container shown in Figure 1.

Figure 3 is a plan view of the opened container shown in Figure 1, showing the closure mechanism.

Figure 4 is a side view of the container opened as in Figure 3.

Figure 5 is a cross section through 5—5 in Figure 1.

Figure 6 is a top plan view with a portion of the top cut away to show the internal construction of my container.

Figure 7 is a detail of the closure mechanism.

Figure 8 is a rear plan view of the top portion of my container.

Figure 9 is a side elevation of Figure 8.

Figure 10 shows my container as in use.

Figure 11 is a plan view of a container with a modified closure mechanism.

Figure 12 is a plan view of said container compressed to open position and showing interior.

Figure 13 is a side view of the spring mechanism 55 of said container.

Figure 14 is a plan view of a spring mechanism with spring ejecting means.

Figure 15 is a cross-sectional view of a container with said mechanism in place.

Referring now more specifically to Figures 1 5 and 2, my container comprises two similar portions of material 2 and 3, which are secured to each other as by sewing along the periphery 4. Any suitable material preferably one having flexibility, such as leather or fabric may be used. 10

The portion 2 may be pan-shaped as in Figure 2, or may, if preferred, be a continuous piece of material.

Portion 3 which constitutes the closure is provided with a slit 7 which extends longitudinally 15 and ending a sufficient distance from the periphery to leave sufficient leather to form a secure pocket.

Along the entire length of the two edges formed by the slit and on the under surface of portion 3, 20 reinforcing members 8 and 9, Figure 3, of any suitable material such as a leather strip are secured in any well known manner as by gluing.

After the container has been assembled to form the construction described above, two tension 25 members such as the spring wires 11 and 12, Figure 7, are inserted within the compartment formed by the two portions of material, 2 and 3.

Members 11 and 12 are of like construction with one end thereof curved as at 13 to form a part 30 of an arc and the opposite end indented to form a hook 14, the under surface of which is shaped to conform, as will appear hereinafter, with the inner surface of the arc 13.

Members 11 and 12 are inverted with respect 35 to each other as shown in Figure 7, so that the arced end 13 of member 11 is adjacent to the hooked end of member 12 and the arc end 13 of member 12 is adjacent to the hook end of member 11, thus forming a ball and socket arrangement. These two members 11 and 12, in this position, are inserted through the opening at 7 into the compartment of the container and assume the position shown in Figure 6.

The length of members 11 and 12 is slightly 45 greater than the inside longitudinal distance between the secured ends of the parts 2 and 3 so that normally both members 11 and 12 are partially compressed and under spring tension, when in position as shown in Figure 6. The spring 50 members are thus locked in position although readily removable.

As will now be clear, the arc at 13 is shaped to conform with the arc formed by the securing edge of the two pieces of material and the surface 55

15 of hook 14 forms a substantially snug fit along the inner surface of arc 13, the portion 2 stretching itself panlike around the spring as shown in Figure 2.

5 Spring members 11 and 12 thus normally tend to stretch portions 2 and 3 longitudinally, thereby automatically holding the slot 7 securely closed, as shown in Figure 1.

10 The rear piece 2 may be perforated as at 16 and 17 through which a link shaped member 18 made of any desired material such as leather is threaded and joined as by a knot shown at 19. Devices such as keys, 21, may depend from link 18 as shown in Figure 10.

15 The operation of the container should now be obvious. Normally, when it is desired to withdraw an article from the container, the container is gripped at points adjacent the ends of springs 11 and 12 as shown in Figures 3 and 4 and 20 compressed against the action of the springs. Slit 17 opens and as the pressure in the springs continues, the opening passes from an elliptical stage to one in which the opening is substantially a circle as shown in Figure 3, thus providing an 25 opening for inserting or withdrawing articles such as key 21. In this position, members 8 and 9 form a reinforcing perimeter to open the slit and keep it substantially circular. To close the container, the link 18 is grasped by the fingers of 30 the user at 19 and pulled until devices such as key 21 are entirely within the enclosing chamber. When now the ends of the container are released, spring members 11 and 12 will automatically move the ends of the container to their maximum 35 longitudinal position, thus automatically and securely closing the slot 7.

As will now be obvious in operating my container, it is not necessary to provide complicated securing means for the spring members 11 and 40 12. In fact, members 11 and 12 can be mounted in place quickly and simply. As shown, the ends of these members form a ball and socket joint, or, if preferred, a pin joint may be provided. As the container is opened and closed, there is substantially 45 no sliding friction between members 11 and 12 and the leather, substantially all of the friction occurring between the members 11 and 12.

An automatic method for ejecting the keys from within the container can be accomplished 50 by extending the free end 15' of the spring 11' shown in Figures 14 and 15 inwardly to a point midway the length of the spring as at 15''. By twisting this spring at 15'', a tension can be created in this extension transverse to that in the 55 main body of the spring. By perforating this extension for inserting a key ring, means will be provided for ejecting the key ring and keys from the center of the container when the container is open. In closing, the container is compressed 60 as hitherto explained, the spring extension depressed with the forefinger, and the container allowed to close on the extension keys and key ring.

In Figure 8 a rear view of the front portion 3 is

shown. Attached longitudinally thereto a reinforcing strip 20 is placed, which may be sewed or glued thereon. Thereafter, a longitudinal slit 22 divides the reinforcing strip into two sections 23 and 24.

5 In Figure 9 the reinforcing strip 20 is shown attached to the front portion 3. The two extreme ends of the reinforcing strip 20 are bevelled so that the front and rear portions 3 and 2 may be sewed together around the periphery 10 without producing obstructions at each end.

The reinforcing strip 20 performs a triple function. It acts to keep the slit 7 closed when the pressure has been released at its ends. It serves to produce a uniformly round opening when the 15 ends are compressed. When the container is closed, the thickness of the reinforcing strip being adjacent the slit 7 serves to deflect the contents away from the opening.

20 As a key container, the contents can be withdrawn by compressing the two extreme ends with one hand, inverting the same thereby causing the keys to be expelled. In closing, knot 19 is pulled away from the container, causing the keys to be withdrawn therein, as previously explained.

25 In Figure 11, a circular container is shown with the front 3' longitudinally slit as at 7', and containing a single closure spring 25 with in-turned ends 26 to avoid sticking into the leather of the container, and providing a minimum of 30 friction. The spring 25 is inserted into the slot and parallel to it, with the in-turned ends towards the opening so that under flexure, as indicated by the dotted lines in Figure 13, the center of the spring will move away from the slit 7'. This is 35 a simplification of the closure mechanism and lowers the manufacturing cost of the container.

It is obvious that new uses may cause slight changes in my invention. Accordingly, I do not wish to be limited to the exact construction as 40 shown, but claim broadly the right to use all equivalent instrumentalities coming within the scope of the appended claims.

I claim:

1. A container comprising a casing, a closure 45 for said casing, a pair of flat wire springs comprising in duplicate spring members, each having a rounded end to form a hook on its outside surface and a curved end to form a socket on its inside surface, said members in juxtaposition to 50 permit the socket of one to engage the hook of the other for providing a substantially frictionless bearing to enable relative movement of said tensioned members.

2. A container comprising a casing having a 55 front and back wall, a closure for said front wall, a pair of flat, normally tensioned, wire springs, the two adjacent ends forming a hook and socket junction at each of the ends of said spring members for providing a substantially frictionless 60 bearing to enable relative movement of said tensioned members.

ALBERT JOHN MEIER.
